(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with graphical user interface according to a first embodiment of the present invention; and,

FIG. 2 is a front view of a display screen with graphical user interface according to a second embodiment of the present invention.

The differences in grayscale of FIG. 2 depicts a contrast in appearance, color, or shade thereof, with no specific appearance, color, or shade thereof being claimed. The broken lines showing a portion of a display screen in FIGS. 1 and 2 is for the purpose of illustrating environmental structure and forms no part of the claimed design.

1 Claim, 2 Drawing Sheets
